United States Patent Office

Doc. 222,777
Patented Dec. 28, 1971

222,777

TABLE BASE OR THE LIKE

Willard M. Fesler, 228 4th St., Manhattan
Beach, Calif. 90266

Filed Aug. 7, 1970, Ser. No. 24,365

Term of patent 14 years

Int. Cl. D6—93

U.S. Cl. D33—14

FIG. 1.

FIG. 2.

FIG. 3.

FIG. 4.

FIG. 1 is a top plan view of a table base, showing my new design;

FIG. 2 is an end elevational view thereof;

FIG. 3 is an upper perspective view thereof; and

FIG. 4 is a side elevational view thereof, taken in the direction of arrow 4 of FIG. 3.

I claim:

The ornamental design for a table base or the like, substantially as shown.
